(57) **CLAIM**

The ornamental design for a bug zapper, as shown and described.

DESCRIPTION

FIG. 1 is a perspective view of a bug zapper;
FIG. 2 is a top plan view thereof;
FIG. 3 is a bottom plan view thereof;
FIG. 4 is a front elevational view thereof;
FIG. 5 is a rear elevational view thereof;
FIG. 6 is a right side elevational view thereof; and,
FIG. 7 is a left side elevational view thereof.
The broken lines shown in the drawing views are included for the purpose of showing environmental structure that forms no part of the claimed design.
